UNITED STATES PATENT OFFICE.

JOHN A. YORK, OF HARTFORD, CONNECTICUT, ASSIGNOR TO THE ARROW ELECTRIC COMPANY, OF HARTFORD, CONNECTICUT, A CORPORATION OF CONNECTICUT.

PUSH-BUTTON SNAP-SWITCH.

No. 876,511.

Specification of Letters Patent.

Patented Jan. 14, 1908.

Application filed July 29, 1907. Serial No. 385,977.

To all whom it may concern:

Be it known that I, JOHN A. YORK, a citizen of the United States, residing at Hartford, in the county of Hartford and State of Connecticut, have invented a new and useful 5 Push-Button Snap-Switch, of which the following is a specification.

This invention relates to an electric switch of the type having movable contacts 10 that are oscillated by push buttons for the purpose of being engaged with and disengaged from stationary contacts to which the circuit wires are connected.

The object of the invention is to provide a 15 simple construction which is sure and positive in action and very cheap to manufacture and assemble.

Figure 1 of the accompanying drawings shows a front elevation of the operating 20 mechanism of a switch that embodies the invention. Fig. 2 shows a rear elevation of the operating mechanism. Fig. 3 shows a side elevation of the same. Fig. 4 shows a front view of the cam plate to which the push 25 buttons are connected. Fig. 5 shows an edge view of the cam plate. Fig. 6 shows a front view of the lock plate. Fig. 7 shows an edge view of the lock plate. Fig. 8 shows a front view of the supporting frame. Fig. 9 30 shows an edge view of the supporting frame. Fig. 10 shows a side view of the locking tumbler.

The inclosing receptacle with the stationary contacts which are necessarily secured 35 to the base of the receptacle, and the face plate are not illustrated for they form no part of the present invention and can be made of any desired material in any common way.

40 The supporting frame 1 may be formed in any desired manner and secured to the base of the receptacle in any convenient way. Loosely held by the supporting frame is a spindle 2. Secured to but insulated from 45 the spindle are the movable contacts 3. Attached to the spindle or to the movable contacts is a plate 4 which has locking shoulders 5 and stop shoulders 6, which latter are adapted to engage lugs 7 preferably 50 thrown backwardly from the supporting frame. Projecting forwardly from the lock plate is an arm 8 and engaging the opposite edges of this arm are the ends of a spring 9 that is coiled upon the hub 10 that projects

from the supporting frame and supports the 55 spindle.

Mounted on the supporting hub is a plate 11 to which the push buttons 12 are connected by the shanks 13. This plate has an arm 16 that projects forwardly parallel with 60 and adjacent to the arm that projects from the lock plate, and is embraced by the opposite ends of the coiled spring. The edge of the plate to which the push buttons are connected is formed with inclined or cam 65 surfaces 14 and embracing this edge of the cam plate is a forked tumbler 15. This tumbler is shown as made of two pieces of metal that are loosely inserted in a slot in the back and a slot in the base of the supporting frame so that as the cam plate is oscillated back and forth by pushing in the buttons, the tumbler is first held backwardly with a part extending through the supporting frame in the path of a locking shoulder of 70 the lock plate and afterwards withdrawn from in front of this locking shoulder so the lock plate can be thrown by the spring.

75 When a button is pressed inwardly and the cam plate is oscillated the cam plate arm 80 engages one end of the coiled spring and places the spring under tension in a common manner. During this period the rear edge of the tumbler is held in the path of the lock plate. After the spring is under sufficient tension the cam 85 plate withdraws the edge of the oscillating tumbler from in front of the locking shoulder and allows the lock plate to be thrown by the push of the other end of the spring against the arm that projects forwardly 90 from the lock plate. The lock plate can not move until a push button has been pushed in a sufficient distance to withdraw the tumbler from the path of the lock plate and the spring is under sufficient tension to throw the 95 lock plate, the spindle and connected movable contacts, with sufficient force to cause them to engage with or be disengaged from the stationary contacts in the proper manner to close or open the circuit. The engagement 100 of the stop shoulders of the lock plate with the stop lugs on the frame stop the parts in the desired positions.

The invention claimed is:

1. An electric switch mechanism having 105 movable contacts, a lock plate connected with and adapted to move the contacts, a cam plate, push buttons connected with and

adapted to move the cam plate, a tumbler adapted to be moved by the cam plate in and out through the supporting plate into and out of the path of the lock plate, and a spiral 5 spring adapted to be placed under tension by the movement of the push buttons and to throw the lock plate and movable poles after the tumbler has been withdrawn from the lock plate by the movement of the cam plate, 10 substantially as specified.

2. An electric switch having movable contacts, a lock plate connected with and controlling the movement of the contacts, push buttons, a cam plate connected with the 15 push buttons, a tumbler moved substantially parallel with the axis of the movable contacts by the movement of the cam plate,

and a spring for throwing the lock plate placed under tension by the movement of the cam plate, substantially as specified. 20

3. An electric switch having movable contacts, a lock plate controlling the movement of the contacts, push buttons, a cam plate moved by the movement of the push buttons, a tumbler moved by the movement 25 of the cam plate transversely of the plane of the movement of the lock plate, and a spring for throwing the lock plate made tense by the movement of the cam plate, substantially as specified.

JOHN A. YORK.
